(57) **CLAIM**

The ornamental design for a silencer cap, as shown and described.

DESCRIPTION

FIG. 1 is an isometric view of a silencer cap in accordance with the present disclosure;

FIG. 2 is a front view of the silencer cap of FIG. 1;

FIG. 3 is a rear view of the silencer cap of FIG. 1;

FIG. 4 is a left side elevation view of the silencer cap of FIG. 1;

FIG. 5 is a right side elevation view of the silencer cap of FIG. 1; and,

FIG. 6 is a top view of the silencer cap of FIG. 1. The broken lines in the Figures are for illustrative purposes only and form no part of the claimed design.
